UNITED STATES PATENT OFFICE.

WILLIAM H. WEEKS, OF OAKLAND, CALIFORNIA.

CHALK RAIL FOR BLACKBOARDS.

Application filed March 15, 1923. Serial No. 625,387.

To all whom it may concern:

Be it known that I, WILLIAM H. WEEKS, a citizen of the United States, and a resident of Oakland, county of Alameda, and 5 State of California, have invented a new and useful Chalk Rail for Blackboards, of which the following is a specification.

The present invention relates to a chalk rail for blackboards and has for its primary 10 object to provide a neat and convenient means for holding chalk beneath a blackboard, such for instance as is employed in school buildings where the blackboard is formed along the walls of the room. One 15 of the important features of the invention resides in providing a screened holder for the chalk so as to do away with the customary chalk dust usually present along the rail of the blackboard. A further object 20 of the invention is to provide hinged means for securing the screen in such a manner that the inner frame holding the screen disappears into a recess in the frame of the blackboard whereby accumulation of dust on the 25 inner frame is prevented.

The invention possesses further features which will appear as the description now proceeds with reference to the illustrative embodiment of the invention as shown in the 30 accompanying drawing, in which Figure 1 is a view in plan of the improved chalk rail, and Figure 2 is a cross section on the line 2—2 of Figure 1.

Referring now to the drawing in detail:

35 Of the frame (1) which surrounds the blackboard (2) only the lower member (3) is shown in the drawing. It is secured in any suitable manner to a suitable support such as the wall (4). Along the lower member 40 of the blackboard frame I use a well (5) projecting outwardly therefrom. The surface of the well is dished out as at (7) to provide a receptacle for collecting the chalk dust.

45 Hingedly connected to the lower member (3) of the blackboard frame, preferably by a hinge such as at (8), is a frame (9), the same including along its front rail a downwardly presented flange (10) adapted to 50 overlie the front edge along the well (5) and with the back rail (11) of the frame received in a recess (12). The under side of the back rail (11) is rounded off so that when the frame is swung upwardly from the

well (5) as shown in dotted lines in Figure 55 2, the back rail (11) may swing clear of the recess.

A screen (13) is carried within the area defined by the frame (9) and made to directly overlie the well so that any chalk dust 60 falling upon the chalk rail will be sifted through the screen and collected in the well, where it may be easily removed by raising the frame, as shown in dotted lines in Figure 65 2, and brushing or otherwise cleaning the well. The screen is preferably confined within the area of the frame by making a rabbeted edge along the inside of the frame rails and using strips (14) to confine the screen upon the shelf-like ledge thus provided.

The well (5) as well as the frame (9) is 70 preferably made in certain lengths, as shown in Figure 1, and the respective ends of the lengths are arranged in confronting relation 75 and with the length of the frame corresponding to the length of the well. Suitable blocks or the like (15) may be used at the confronting ends of the well and frame sections, and to add rigidity to the frame it is further 80 suggested to use transverse wooden dowels (16) between the front and back rails of the frame beneath the screen (13).

Various changes in the details may be resorted to without departing from the spirit 85 of the invention as defined by the subjoined claims.

I claim:

1. A chalk rail for a blackboard having a frame around the same comprising a well disposed longitudinally along the lower member of the blackboard frame and projecting outwardly thereof, a second frame hinged to the front of said blackboard frame having a rear rail disappearing in a recess in said member adapted to swing to and from a position over said well and a screen within the area defined by said frame substantially as and for the purpose described.

2. A chalk rail for a blackboard having a frame around the same comprising a well projecting outwardly along the bottom member of the blackboard frame, a second frame hingedly connected to the bottom member adapted to swing to and from a position over the well and including a screen within the area defined by said frame, the back member of the second frame adapted

to be received in a recess and with the hinge connection made above said recess, substantially as and for the purpose described.

3. In combination, a blackboard frame including a well portion and a longitudinal recess above and at one side of the well portion, and a screen supporting frame hingedly sustained on the first frame to occupy spanning or non-spanning position with respect to the well portion and having a portion working in said recess.

4. In combination, a blackboard frame including a well portion and a longitudinal recess above and at one side of the well portion, a screen supporting frame hingedly sustained on the first frame to occupy spanning or non-spanning position with respect to the well portion and having a portion working in said recess, and a depending flange on the supporting frame adapted to overhang the outer edge of the blackboard frame to prevent escape of dust from the well portion.

5. In combination, a blackboard frame including a well portion, a screen supporting frame hingedly sustained on the first frame to occupy spanning or non-spanning

position with respect to the well portion, and projecting beyond the same and a depending flange on the projection adapted 30 to overlap the outer edge of the well portion for the purpose described.

6. In combination, a blackboard frame including a well portion and a longitudinal recess above and at one side of the well portion, and a screen supporting frame hingedly sustained on the first frame to occupy spanning or non-spanning position with respect to the well portion and having 35 a curved portion working in said recess. 40

7. In combination, a blackboard frame including a well portion and a longitudinal recess above and at one side of the well portion, a screen supporting frame hingedly sustained on the first frame to occupy spanning or non-spanning position with respect 45 to the well portion and having a curved edge working in said recess, and a flange depending from a projection of the supporting frame disposed in overlapped relation 50 to the outer edge of the well portion for the purpose described.

WILLIAM H. WEEKS.
